T. SARG

Des. 111,731

SCARF OR SIMILAR ARTICLE

Filed Sept. 9, 1938

INVENTOR: TONY SARG
By His
ATTORNEY J.B. Felshin

UNITED STATES PATENT OFFICE

111,731

DESIGN FOR A SCARF OR SIMILAR ARTICLE

Tony Sarg, New York, N. Y.

Application September 9, 1938, Serial No. 79,815

Term of patent 3½ years

To all whom it may concern:

Be it known that Tony Sarg, a citizen of the United States and resident of New York city, in the county of New York, State of New York, has invented a new, original, and ornamental Design for a Scarf or Similar Article, of which the following is a specification, reference being had to the accompanying drawing, forming part thereof, and in which,

The single figure of the drawing illustrates a scarf embodying my new design.

I claim:—

The ornamental design for a scarf or similar article, substantially as shown.

TONY SARG.
